UNITED STATES PATENT OFFICE.

FRANK KOENIGKRAMER, OF CINCINNATI, OHIO, ASSIGNOR OF ONE-HALF TO
FREDERICK KOENIGKRAMER, OF CINCINNATI, OHIO.

HYDRAULIC LIFTING MECHANISM.

1,164,290.

Specification of Letters Patent. Patented Dec. 14, 1915.

Application filed October 25, 1913. Serial No. 797,323.

To all whom it may concern:

Be it known that I, FRANK KOENIGKRAMER, citizen of the United States, residing at Cincinnati, in the county of Hamilton 5 and State of Ohio, have invented certain new and useful Improvements in Hydraulic Lifting Mechanism, of which the following is a specification.

My invention relates to hydraulic mechanism for operating chairs and tables for 10 barber, dental, and surgical purposes. One of its objects is to provide improved and simple liquid pumping mechanism and releasing mechanism.

Another object is to provide improved and 15 reliable brake or locking mechanism capable of being operated with a minimum of strain or vibration.

Another object is to provide improved 20 mechanism to lock and release the reclining mechanism with a minimum of strain or vibration.

Another object is to provide for carrying 25 out the several operations with a single improved lever mechanism.

My invention also comprises certain 30 details of form, combination, and arrangement, all of which will be fully set forth in the description of the accompanying drawings, in which:

Figure 1 is a central vertical section on line *v v* of Fig. 3, of my improved mechanism. Fig. 2 is a central vertical section through the same at right angles to Fig. 1, 35 on line *z z* of Fig. 3. Fig. 3 is a top plan view upon an enlarged scale. Fig. 4 is a perspective view of the crank pin and cam member carried at the inner end of the actuating lever. Fig. 5 is a bottom plan 40 view of the hydraulic plunger. Fig. 6 is a bottom plan view of the pump piston. Fig. 7 is a sectional detail of the lower end of the plunger and piston in position to release the liquid. Fig. 8 is a similar view showing 45 the plunger and piston in a different position. Fig. 9 is a perspective view of the brake or locking member detached. Fig. 10 is a perspective view of the member employed to lock and release the reclining bar, 50 detached. Fig. 11 is a sectional detail through the plunger similar to Fig. 2, and illustrating a modification.

The accompanying drawings represent the preferred embodiment of my invention, in which—

A represents the cylinder and B the plunger of a hydraulic lifting mechanism, the cylinder being usually mounted upon a base or standard, and the plunger attached to the body of a chair or table to be lifted and lowered or reclined by said mechanism. At the lower end of the plunger is a detachable head 2 provided with a port 3 and a valve 4 held in place by a flat spring 5 held by a screw 6 to the under face of said head. An 65 upwardly projecting post 7 having an annularly reduced portion or neck 8 is carried by the head 2. Mounted within the cylindrical bore of the plunger B is a piston head D which is connected by a wrist pin 9 with 70 a pitman 10 to reciprocate said piston head within the plunger. Said piston head is preferably of the cup-shaped type with a section of the side wall cut away at 45 to admit the brake or locking member Fig. 9. 75 Said piston head is provided with a port closed by a valve 11 held in place by a spring 12 fastened by a screw 14 to the face of the piston head. A screw 15 is also tapped into said piston head in line with the port 3 and 80 valve 4, and is adjustable so as to engage and open the valve 4 at a predetermined position of the piston head. The pitman 10 is preferably of yoke shape at its lower end and a roller 16 is mounted upon the wrist 85 pin between the forks of said pitman. A recess 17 through the center of the piston head permits the passage of the post 7, the greater circumference of said post being closely fitted by said recess. The vertical 90 dimension of said recess is practically the same as the vertical dimension of the head section of the post 7, and slightly less than the vertical dimension of the port or neck portion of said post.

An operating lever E is journaled in a bearing in one side of the upper portion of the plunger B, and the outer upwardly turned end of said lever is provided with a handle. To the inner end of said lever is 100 firmly secured by set screws 18 a head or collar 19 which carries a crank pin 20 to which the upper end of the pitman 10 is journaled. Said head also carries a cam or

tooth 21 to engage the upper end of a bar 22 to shift said bar endwise. Another cam 24 carried by the head 19 engages a roller 25 to release a reclining bar and permit the 5 chair or table top to be inclined at an angle.

The reclining bar 26 is seated at the upper end of the plunger in perforations in opposite sides of said plunger. Said bar also passes through perforations 27 in opposite 10 ends of a yoke shaped lever 28 which is pivotally supported with reference to the plunger by rod 29. The opposite or free end of the lever 28 has journaled thereto the roller 25 in the path of the cam 24 by means of 15 which the lever 28 may be depressed. Coiled springs 30 are interposed between the lever 28 and the face of the plunger, and held against displacement by lugs projecting downwardly into said springs from the lever 20 28, said springs tending to elevate the free end of lever 28, and thereby to frictionally lock the reclining bar against endwise displacement where it passes through the perforations in the plunger and the perforations in the lever 28. It will be noted that 25 by passing the reclining bar through perforations in both the plunger and lever 28, said lever will have a double locking action, due to forcing the perforations through 30 which said reclining bar passes out of alignment either upwardly or downwardly, and hence either the cam or the spring pressure may be utilized to retain the reclining bar in its adjusted position. By passing the 35 reclining bar through closely fitting perforations in both the plunger and lever 28, a firm locking action is obtained with a minimum of wear on the locking members and a minimum action to release the bar. The engagement of the cam 24 with the roller 25 to 40 release the reclining bar can also be effected with practically no friction and consequently without strain or vibration of the chair or table.

The throw of the lever E enables the piston head D to assume several different positions with reference to the post 7, as illustrated in Figs. 1, 2, 7, and 8, and also a pumping position intermediate of that 45 shown in Figs. 2 and 7. Thus in substantially the position illustrated in Figs. 1 and 2 the crank pin 20 is on dead center, and the piston head is held practically stationarily with reference to the plunger, also the 50 recess 17 is above and out of engagement with the post 7, forming a port for the free passage of fluid through the piston head. In this position the valve 4 is closed and resists the tendency of liquid to escape upwardly from below the plunger. As the 55 crank pin 20 approaches a dead center and the piston head comes to rest at the upward limit of its stroke, the cam 21 engages a notch or recess 32 in the upper end of bar 60 22 and quickly thrusts said bar endwise downwardly. The lower end of the bar 22 rides in a channel shaped groove 33 in the rear face of a brake shoe 34 which is seated in a recess in the side wall of the plunger B in position to frictionally engage the inner 65 face of the cylinder A to lock the plunger and cylinder firmly together. The lower end of the bar 22 is wedge shaped and when thrust downwardly engages between the grooved portion of the brake shoe and the 70 roller 16 of the piston head, forcing the stationary piston head against one side or face of the inner wall of the plunger and forcing the brake shoe in the opposite direction through the perforation in the plunger 75 against the inner wall of the cylinder. The action between the wedge and the roller are such as to enable this locking operation to be effected with practically no strain or vibration imparted to the chair or table, and 80 with the piston head at rest in the plunger. A movement of lever E in the reverse direction causes the cam 21 to engage the upper projection 35 of bar 22 to lift said bar. A 85 bolt 36 passing through a slot 37 in the plunger wall and threaded into the bar 22 serves in connection with a coiled spring 38 on said bolt to yieldingly hold said bar in 90 position. The engagement of the bar 22 in the channel shaped recess of the brake shoe 95 holds the brake shoe in position and in alignment with the cylinder wall. As the lever E, Fig. 2, is moved toward the right, and while the recess 17 is still out of engagement with the upper end of post 7, the cam 100 24 engages the roller 25 to depress the lever 28 to release and permit readjustment of the reclining bar 26. Further movement of the lever E to the right, Fig. 2, disengages cam 24 and roller 25 relocking the reclining bar, 105 and brings the recess 17 into engagement with the upper enlarged portion of post 7, closing recess 17 and cutting off a flow of liquid through said recess. In this position an oscillating movement of the lever E causes 110 liquid to be pumped or forced downwardly through the valves 11 and 4, thus forcing the plunger to a higher position in the cylinder. The limits of this oscillating movement of lever E are indicated approximately 115 by the dotted lines 40 and 41. Further movement of lever E to the right, Fig. 2, shifts the piston head to the position illustrated in Fig. 7 with the recess 17 opposite the neck or port 8 of post 7, and with the 120 valve 4 held in open position by the screw 15. In this position liquid is enabled to flow in considerable volume through the valve 4 and upwardly around the neck 8 through the recess 17, causing the plunger to descend into the cylinder. A still further movement of the lever E to the right, Fig. 2, causes the piston head to assume the position illustrated in Fig. 8, in which the lower enlarged 125 portion of post 7 entirely closes and cuts off 130

a flow of liquid through recess 17, and locks the plunger without vibration against further descent, the valve 4 remaining open.

In the modification Fig. 11 I have illustrated a tapered or inclined face 42 carried by the piston head between the forked arms of the pitman, and a roller 16' carried by the lower end of the bar 22' corresponding to the bar 22 of Fig. 2, to engage with and ride upon said inclined face to force the brake shoe into engagement with the inner wall of the cylinder to lock the plunger thereto. In like manner if desired the roller 25 and cam 24 may be transposed in position to that illustrated in Fig. 2.

As the patient or occupant of the chair or table is particularly sensitive to strains or vibrations imparted to the chair or table in operating the same, it is important to reduce such strains and vibrations to a minimum, which is effected in all the movements of my improved mechanism. Also the several different operative positions of the piston head enable the desired movements to be advantageously effected with a single operating lever, and the plunger locked while said head is in idle stationary position.

The mechanism herein illustrated and described is capable of considerable modification without departing from the principle of my invention.

Having described my invention, what I claim is:

1. A hydraulic lifting mechanism comprising a cylinder, a hollow plunger seated therein and provided with a valved port leading from the interior of said plunger to the cylinder beneath said plunger, a post carried rigidly by said plunger and projecting upwardly into the interior of said plunger from the bottom thereof with a fluid port intermediate of its ends, a piston head to reciprocate within said plunger and provided with a valved port leading downwardly therethrough and a through recess to receive and closely fit said post, an operating lever journaled at the upper end to said plunger, and a pitman connecting said piston head to said operating lever to reciprocate said piston head.

2. A hydraulic lifting mechanism comprising a cylinder, a hollow plunger seated therein and provided with a valved port leading from the interior of said plunger to the cylinder beneath said plunger, a post carried rigidly by said plunger and projecting upwardly into the interior of said plunger and provided with a fluid port intermediate of its ends, a piston head to reciprocate within said plunger, means carried by said plunger to reciprocate said piston head, said piston head being provided with a valved port leading downwardly therethrough, a through recess to receive and closely fit said post and means to open the

valve controlling said plunger port at a predetermined position of said piston head.

3. A hydraulic lifting mechanism comprising a cylinder, a hollow plunger seated therein and provided with a valved port leading from the interior of said plunger to said cylinder beneath said plunger, a piston head to reciprocate within said plunger and provided with a valved port leading downwardly therethrough, an operating lever journaled to said plunger and provided with a crank pin, and a cam, a pitman connecting said piston head to said crank pin, a brake shoe seated in a recess through the side wall of said plunger opposite the upper limit of the movement of said piston head to bear upon the inner wall of said cylinder, a bar having sliding engagement with said brake shoe and adjustable endwise by said cam, said bar and piston head being provided with an inclined face and a roller to wedge said bar between said piston head and brake shoe to lock said cylinder and plunger together.

4. A hydraulic lifting mechanism comprising a cylinder, a hollow plunger seated therein and provided with a valved port leading from the interior of said plunger to said cylinder beneath said plunger, a piston head to reciprocate within said plunger and provided with a valved port leading downwardly therethrough, an operating lever journaled to said plunger and provided with a cam, a pitman connecting said piston head to said operating lever, a brake shoe seated in a recess through the side wall of said plunger opposite the upper limit of the movement of said piston head to bear upon the inner wall of said cylinder, a bar having sliding engagement with said brake shoe and adjustable endwise by said cam and having an inclined face, and a roller carried by said piston head to engage said inclined face to wedge said bar between said piston and brake shoe to lock and release said brake shoe.

5. A hydraulic lifting mechanism comprising a cylinder, a hollow plunger seated therein, a piston head to reciprocate within said plunger, an operating lever journaled to said plunger and connected by a pitman with said piston head, a brake shoe to engage the inner wall of said cylinder through a recess in the plunger wall, and means interposed between said brake shoe and said piston-head when stationary at the limit of its upward stroke and operably connected to said operating lever to force said brake shoe and piston head apart to lock said cylinder and plunger together.

6. A hydraulic lifting mechanism comprising a cylinder, a hollow plunger seated therein and provided with a valved port leading from the interior of said plunger to said cylinder below said plunger, a post pro-

- jecting upwardly within said plunger from its bottom, a piston head to reciprocate within said plunger and provided with a valved port leading downwardly therethrough, a through recess to receive said post and a stud to open the valve of said plunger port, and means to reciprocate said piston head from a position above and clear of the upper end of said post to a position below the port in said post, thereby as said piston head moves downwardly providing therefor successively an idle position, a pumping position and a fluid release position.
7. A hydraulic lifting mechanism comprising a cylinder, a hollow plunger seated therein and provided with a valved port leading from the interior of said plunger to said cylinder below said plunger, a piston head to reciprocate within said plunger and provided with a valved port leading downwardly therethrough, a downwardly projecting stud to open the valve of said plunger port, and a vertical through recess, a post projecting upwardly within said plunger from its bottom to engage said through recess through a portion of the piston head stroke, said post being provided with a port in its middle section, a brake shoe seated in a recess through the plunger wall at the

upper limit of movement of said piston head, an operative lever to reciprocate said piston head, and means interposed between said piston head and brake shoe to lock said brake shoe to the inner wall of said cylinder.

8. A hydraulic lifting mechanism comprising a cylinder, a hollow plunger seated therein and provided with a valved port leading from the interior of said plunger to said cylinder below said plunger, a piston head to reciprocate within said plunger, a brake shoe seated in a recess through the side wall of said plunger at the upper limit of the piston head stroke, an operating lever provided with a cam and connected by a pitman to said piston head, a roller journaled upon the wrist pin of said piston head and a wedge shaped bar operated by said cam and engaging said roller and brake shoe to releasably lock said cylinder, plunger, piston head and brake shoe together when said piston head has reached a stationary position at the limit of its stroke.

In testimony whereof I have affixed my signature in presence of two witnesses.

FRANK KOENIGKRAMER.
